DESIGN FOR A BASE FOR HAIR WAVING MACHINES

Floyd V. Schleimer, San Francisco, Calif., assignor to Duart Manufacturing Co. Ltd., formerly Pacific Hair Goods Company, San Francisco, Calif., a corporation of California

Application September 21, 1937, Serial No. 71,708

Term of patent 7 years

To all whom it may concern:

Be it known that I, Floyd V. Schleimer, a citizen of the United States and a resident of the city and county of San Francisco, State of California, have invented a new, original, and ornamental Design for a Base for Hair Waving Machines, of which the following is a specification, reference being had to the accompanying drawing forming part thereof.

Referring to the drawing:
Fig. 1 is a front elevational view of a base for a hair waving machine, showing my new design.
Fig. 2 is a top plan view.

Fig. 3 is a side elevational view thereof.

I claim:

The ornamental design for a base for hair waving machines, as shown.

FLOYD V. SCHLEIMER.
